UNITED STATES PATENT OFFICE.

STEVEN BRENDZA, OF CLEVELAND, OHIO.

STAIR-CARPET FASTENER.

1,321,507.

Specification of Letters Patent. Patented Nov. 11, 1919.

Application filed April 9, 1919. Serial No. 288,819.

To all whom it may concern:

Be it known that I, STEVEN BRENDZA, a citizen of the United States, residing at Cleveland, in the county of Cuyahoga and 5 State of Ohio, have invented a certain new and useful Improvement in Stair-Carpet Fasteners, of which the following is a full, clear, and exact description, reference being had to the accompanying drawings.

10 This invention relates generally to carpet fasteners and more particularly to a device for fastening a strip of stair carpet to the stairs in such a manner that said stair carpet can be quickly and easily removed and re- 15 placed when desired.

Another object of the invention is to provide a stair carpet fastener embodying these advantageous features which will be inexpensive to manufacture and can be easily 20 applied without the aid of a skilled mechanic.

With these objects in view the invention consists in the novel features of construction, combination and arrangement all of 25 which be fully described hereinafter and set forth in the appended claims.

In the drawings forming a part of this specification Figure 1 is a front elevation of a portion of stairs with carpet applied 30 thereto and secured by means of my improved fastener; Fig. 2 is a detail sectional view on the line 2—2 of Fig. 1; Fig. 3 is a detail view illustrating the engagement of the hooked rod with the corner plate; and 35 Fig. 4 is a detail view showing the corner plate and end of rod disconnected.

In the practical embodiment of my invention I employ a pair of apertured corner plates A which are adapted to be secured in 40 the opposite angles of the stairs formed between the tread and riser and the stringer at the side thereof. These corner plates are preferably triangular in shape and are concavo-convex as shown, each plate 45 being formed with a substantially central aperture A' through which a fastening screw B is adapted to be passed for the purpose of securing the plate in position. Each plate is also provided with an 50 aperture C which is preferably arranged upon a line extending from the aperture A'

to the inner corner of the triangular plate A. The carpet to be secured is indicated at D and this is arranged in the usual manner upon the stairs and in order to secure this 55 carpet properly in the angle between the tread and riser I provide a fastening means comprising a tube E and rods F, the inner ends of the rods fitting into the opposite 60 ends of the tube E and the outer ends F' 65 of the rods are projected into the opening C and in order to prevent any lateral movement of these ends after having been properly positioned in the openings, I provide a shoulder or bend or upset portion F² be- 70 tween the rod F and the extreme end F', this bend or upset portion being quite short so that the end F' can be inserted into the opening C and then by proper manipulation the bend or upset portion F² can be intro- 75 duced into the opening thereby bringing the rod into locked engagement with the corner plate.

In operation after the carpet has been properly arranged upon the stairs the rods 75 are brought into engagement with the corner plates and then the tube or sleeve is brought into engagement with the inner ends of the rods practically making a continuous rod from corner to corner of the stairs and ex- 80 tending across the strip of carpet holding it properly positioned in the angle between the tread and riser.

When it is desired to remove the carpet it is only necessary to slip the tube or sleeve 85 sufficiently to one side to disengage one of the rods and then the other rod can be quickly disengaged and the cap is entirely free to be removed. It will thus be seen that I provide an exceedingly simple and inex- 90 pensive construction of stair-carpet fastener capable of carrying out all of the objects hereinbefore referred to.

Having thus described my invention, what I claim is:—

1. In a stair-carpet fastener the combination with a pair of perforated corner plates, of rods having hooked ends engaging said plates, and a tube connecting the opposed ends of said rods.
2. In a stair carpet fastener, the combination with rods having hooked outer ends, of

a tube engaging the inner ends of said rods, and means located at the opposite sides of the stairs with which the hooked ends of the rods are engaged.

5 3. In a stair carpet fastener, the combination with a pair of perforated corner

plates, of rods having their outer ends in engagement with said plates, and a tube engaging the opposed ends of said rods.

In testimony whereof I hereunto affix my 10 signature.

STEVEN BRENDZA.
